L. L. COWELL & G. UNSER.
WINDOW SCREEN.
APPLICATION FILED JUNE 8, 1908.

916,389.

Patented Mar. 23, 1909.

UNITED STATES PATENT OFFICE

LEO L. COWELL AND GEORGE UNSER, OF LUDINGTON, MICHIGAN.

WINDOW-SCREEN.

No. 916,389.

Specification of Letters Patent. Patented March 23, 1909.

Application filed June 8, 1908. Serial No. 437,441.

To all whom it may concern:

Be it known that we, LEO L. COWELL and GEORGE UNSER, citizens of the United States, residing at Ludington, in the county of Mason and State of Michigan, have invented certain new and useful Improvements in Window-Screens; and we do declare the following to be a full, clear, and exact description of the invention, such as will enable others skilled in the art to which it appertains to make and use the same.

This invention relates to an improved spring roller window screen.

The object of the invention is to provide a simply constructed and efficient spring roller screen the casing of which may be mounted on a window sill and the screen fabric detachably connected at its free end to the lower rail of the window sash without injuring or marring either.

Another object of the invention is to provide means for holding the roller stationary against the tension of its spring when it is desired to substitute new screen fabric.

With these and other objects in view, the invention consists of certain novel features of construction, combination and arrangement of parts, as will be more fully described and particularly pointed out in the appended claims.

In the accompanying drawings, Figure 1 represents a front elevation of a window with this improved screen applied and with parts broken out, the window sash being shown in raised position; Fig. 2 is a longitudinal section through the casing and roller; Fig. 3 is a transverse vertical section through the casing on line 3—3 of Fig. 1 with the screen enclosed therein; Fig. 4 is a perspective view of the spring roller detached and shown with one end of the screen fabric connected therewith, parts of said roller being broken out. Fig. 5 is a fragmentary perspective view partly in section.

In the embodiment illustrated, a tubular casing 1 is shown of any desired shape and preferably of a length corresponding to the width of the window to which it is to be applied. This casing is provided with apertured feet as 2 for securing it by means of screws or other fastening devices to the window sill as is shown in Fig. 1. The rear side of this casing is provided with a longitudinal slot 3 extending the length thereof and preferably provided at its opposite edges with out-turned flanges as 4, for a purpose to be

described. This casing is provided at its opposite ends with closures 5 and 6 having apertures formed in the centers thereof and provided with inwardly extending sleeves or thimbles as 7 and 8 attached thereto for a purpose to be described. A short shaft 9 is inserted through one end of the casing and projects for a suitable distance beyond the sleeve therein and is fixed to said sleeve to prevent rotation thereof. A tubular roller 10 is mounted within said casing at its opposite ends on the sleeves 7 and 8 and adapted to revolve thereon. This roller is preferably formed of sheet metal and is slit longitudinally as at 11, throughout the length thereof and one edge of said slit has tongues as 12, formed thereon by slitting the tube transversely a short distance, and these tongues are bent back to form connecting members 75 to receive the screen fabric as hereinafter described.

A solid core 13 is disposed within the roller 10 and is fixed thereto, preferably by means of screws which pass through the tube at 80 opposite sides of the slit therein and are engaged with said core to hold it rigidly against turning. A coil wire spring 14 is arranged within the roller 10 between the outer end of the core 13 and the inner end of the shaft 9 and is secured at its opposite ends to said core and shaft respectively, whereby it is adapted to exert a winding tendency on the roller 10. This roller 10 is preferably made of less length than the casing 1 and the end thereof which is engaged with the sleeve at the shaft carried end thereof is adapted to be moved longitudinally thereon to cause it to clamp said sleeve and hold said roller against turning when desired. The inner end of the core 13 is beveled and is adapted to be engaged by a key 15 which is inserted through the open end of the casing and is designed to force the roller in the opposite direction and cause the end thereof to bind on the sleeve 7 which as shown at the right of the casing (Fig. 2) has, as its outer end is approached an external diameter greater than the internal diameter of the co-acting end of roller 10 and hold it against turning when it is desired to insert 105 a new piece of screen fabric in place of an old one which may have become worn or disfigured.

The screen fabric 17 is preferably provided at one end with a reinforcing plate 18 which is adapted to be inserted between the tongues 12 and the outer face of the tube or roller 10

and clamped thereby in operative position. The other end of the screen is clamped between a member 19 preferably composed of a wooden strip. The opposite ends of this strip are cut out on one face thereof, as shown at 20 for a purpose to be described. A metal plate 21 is arranged on the other side of said screen end and is secured to the wooden strip by means of screws or other suitable fastening devices and is provided with apertures adapted to register with the apertures in the strip to permit the screws or other fastening means to pass therethrough for securing the screen to the lower rail of a window sash. This plate 21 is provided with a downwardly inclined flange 22 which is adapted to engage with one of the flanges 4 on the casing 1 when the window is in lowered position to lock the screen to said casing.

20 Guide strips 23 and 24 are adapted to be secured to the opposite sides of the window frame by means of apertured lugs as 25, or in any other desired manner, and are preferably composed of pieces or strips of sheet metal folded longitudinally with the sides thereof spaced apart a sufficient distance to receive the edges of the screen fabric and permit it to slide freely therein and into which the ends of the plate 21 are adapted to slide, one member of the guide strip passing between said ends and the cut-away end portions 20 of the wooden strip 19.

When it is desired to insert a new piece of screen fabric it is only necessary to insert the 35 key 15 with the beveled end thereof first through the open end of the casing 1 and force the roller longitudinally into clamping engagement with the sleeve at the spring carried end thereof and then turning said 40 roller until the clamping tongues come opposite the slot 3 in the casing, when the tongues 12 may be pressed open and the old screen fabric removed, a new piece inserted in its place and the device again pressed into clamping 45 contact therewith.

From the foregoing description, taken in connection with the accompanying drawings, the construction and operation of the invention will be readily understood without requiring a more extended explanation.

50 Various changes in the form, proportion and the minor details of construction may be resorted to without departing from the principle or sacrificing any of the advantages of 55 the invention, as defined in the appended claims.

We claim as our invention:

1. A spring roller screen comprising a tubular casing provided with means for attachment to a window sill and having a slot or opening extending longitudinally thereof, bearings arranged at opposite ends of said casing and comprising inwardly projecting

cylindrical members, a split tubular spring roller mounted in said casing on said cylindrical members, said roller being shorter than the casing and adapted to move longitudinally therein on said cylindrical members, screen fabric connected with said roller and means for holding said roller against turning. 65

2. A spring roller screen, comprising a tubular casing provided with means for attachment to a window sill and having a slot or opening extending longitudinally thereof, a split tubular roller mounted at opposite ends 75 on said cylindrical members, a spacing core arranged in said roller intermediately of its ends and fixed thereto at opposite sides of the slit therein, a coil spring disposed in said roller and connected at one end to one of said cylindrical members and at its other end to said core, means for detachably connecting a screen fabric to said roller, and means for holding said roller against turning. 80

3. A spring roller screen comprising a tubular casing provided with means for attachment to a window sill and having a slot or opening extending longitudinally thereof, cylindrical members projecting inwardly into said casing from the opposite ends thereof, 90 a split tubular roller mounted at opposite ends on said cylindrical members, a spacing core arranged in said roller intermediately of its ends and fixed thereto at opposite sides of the slit therein, a coil spring disposed in 95 said roller and connected at one end to one of said cylindrical members and at its other end to said core, said core having its outer end beveled, a key adapted to be inserted in said roller and having a beveled end to fit against the beveled end of said core for forcing the roller against the tension of its spring to frictionally engage the cylindrical member on which said spring carried end is mounted. 100

4. A spring roller screen comprising a tubular casing provided with means for connecting it to a window sill cylindrical members projecting into said casing from the opposite ends thereof, a split tubular spring roller mounted at its opposite ends on said 110 cylindrical members, means for connecting the opposite edges of said split roller intermediately of its ends, tongues cut out from one edge of said slit and folded to form screen fabric clamping members, and means for locking said roller against turning when desired. 115

In testimony whereof we have hereunto set our hands in presence of two subscribing witnesses.
